MITER-BOX.

1,203,417.

Specification of Letters Patent.

Patented Oct. 31, 1916.

Application filed June 17, 1916. Serial No. 104,167.

To all whom it may concern:

Be it known that we, EDMUND A. SCHADE and CHRISTIAN BODMER, citizens of the United States of America, residing at New 5 Britain, Connecticut, have invented a new and useful Miter-Box, of which the following is a specification.

This invention has for its objects to provide a simple, inexpensive form of length 10 stop for miter boxes which can be readily set and adjusted to suit different conditions and requirements and which when not in use can be stored away within the miter box ready for use at any time.

15 Special objects are to provide a practical gage for unusually long work and to provide for the proper support of long pieces of material being sawed.

In the accomplishment of these objects 20 and others, as will later appear we employ a stop which is adjustable toward and away from the miter box and provide this stop with means for supporting as well as gaging the end of the material being handled. The 25 stop is usually made longitudinally adjustable on a gage rod which is itself preferably adjustably mounted on the miter box and the stop further is adapted to receive and support a stop rod which may be adjusted 30 with respect to the miter box.

Other features of the invention are the provision of means for coupling the rods together to enable the length stop being positioned at some distance from the miter 35 box and the housing of these rods within the base portion of the miter box.

Other features and details of the invention will become apparent as the specification proceeds, attention being directed to the 40 accompanying drawing forming a part hereof and wherein we have shown the invention embodied in a practical and preferred form.

In said drawing: Figure 1 is a perspective view of the invention as applied to a 45 miter box of preferred construction and illustrating the gage employed for short-length work. Fig. 2 is a similar view showing the gage device extended for long work. Fig. 3 is a broken view showing the parts 50 as stored when not in use in the base of the miter box.

The miter box in connection with which the invention is illustrated is shown as made up of a platform or sawing table 7, and back

8 supported by a base portion having supporting legs or feet 9, the saw 10 being guided in the angularly adjustable guides 11. 55

Mounted on the miter box is a supporting and gaging rod 12, said rod being supported, in the present instance, in the longitudinally aligned sockets 13 provided in the supporting legs of the box and adjustably held in such sockets by means of the clamping screws 14.

15 designates the stop or gaging device made, in the present disclosure, with a relatively flat supporting base 16, a supporting column 17 rising from said base and a head 18 on the upper end of said column provided with stop shoulders 19 at the opposite sides 70 thereof and oppositely extending lateral supporting shelves 20 on the base of said shoulders. This head 18 has an opening 21 extending therethrough forming a sleeve for a stop rod 22 and the base portion of the 75 gage has an opening 23 therethrough forming a sleeve receiving the gage rod 12. Clamping screws 24 and 25 are provided for securing the stop in adjusted position on the gage rod and for securing the stop rod 80 22 in adjusted position respectively.

When sawing relatively short lengths of material the stop may be adjusted to a convenient position on the gage rod 12 and the stop rod 22 may then be accurately set 85 to bring the material to the proper length. Another method is to bodily adjust the gaging device, carrying with it the stop rod on the gage rod, or the same results may be obtained by clamping the gage device 90 fast on the gage rod and then adjusting the gaging device to a proper distance from the miter box and securing the gage rod to such point by means of the clamp 14.

The flat supporting base of the gage device provides a firm support for such device thereby enabling the easy and accurate setting of the device. This base also gives the gaging device sufficient rigidity to withstand the shocks of the material being 100 brought into gaging relation therewith.

The gage and stop rods may be made of any convenient length and provision is made for handling extraordinarily long work by coupling the two rods together, this condition being illustrated in Fig. 2 wherein a sleeve coupling 26 is used for uniting adjoining ends of the rods, said rod ends being 105

secured in said coupling by screws 27 and the gage device being in such case engaged on the thus extended gage rod. In this case the shoulder 19 serves as the stop for the work and the end of the work is supported by resting on the supporting shelf 20. This prevents sagging of a long piece of work and assists in holding the work in place.

10 The gaging device may if desired, be secured in adjusted relation by suitable screws or other fastening means passed through the opening 28 provided for that purpose in the base of the device. The construction described provides for a practically unlimited range of adjustment.

When the length gage is not in use it may conveniently be stored in the base portion of the miter box, the at-present preferred method being as indicated in Fig. 3, to store the stop rod 22 in holes 29 provided in the legs of the box and to mount the gaging device on the extended ends of the two rods, the rods being spaced by these holes 25 a distance apart equal to the distance between the sleeves 21 and 23. By such means the gage when not in use is stored out of the way and when needed is at hand so that it may quickly be placed in position.

30 From the illustration it will be apparent that the gage may be used at either end of the miter box and may be set for practically any length of cut.

What we claim is:

35 1. The combination with a miter box, of a longitudinally disposed rod adjustably secured to said box and extensible longitudinally beyond the end of the same, a stop sleeved on said rod and adjustable longitudinally thereon and therefore adjustable longitudinally with respect to the miter box, said stop having a sleeve disposed longitudinally of the miter box and a stop rod longitudinally adjustable in said sleeve.

40 2. The combination with a miter box, of a guiding rod disposed longitudinally of the miter box and extensible longitudinally beyond the end of the miter box, a stop sleeved on said guide rod, adjustable thereon longitudinally with respect to the miter box and provided with a base disposed in the plane

of the base of the miter box to thereby rest upon and be sustained by the support on which the miter box is mounted, said stop having a sleeve disposed longitudinally of the miter box and a longitudinally adjustable stop rod engaged in said sleeve.

3. The combination with a miter box provided with a plurality of holes in the base thereof for receiving and supporting a plurality of separate rods, a plurality of independent rods engaged in said holes and thereby normally housed in the miter box, a clamping means for securing one of the rods in the hole in which it is seated, a coupling having sockets for receiving adjoining ends of the rods for uniting one of the other rods in end-to-end relation to said held rod and a stop engaged on said thus-extended rod.

4. The combination with a miter box, of a length stop adjustable toward and away from the end of the miter box, said stop having oppositely facing stop shoulders, a rod receiving opening extending from one stop shoulder through to the opposite stop shoulder and supporting shelves extending in opposite directions from the stop shoulders in substantially the plane of the sawing platform of the miter box whereby said length stop may be used at either end of the miter box.

5. As an article of manufacture, a length stop for miter boxes having a supporting base, a column rising from said base, oppositely faced stop shoulders on the upper end of said column, oppositely extending supporting shelves projecting laterally from said stop shoulders, said stop having a rod receiving opening extending through said stop shoulders and rod clamping means associated with said opening.

6. In combination, a length gage having spaced rod receiving sleeves, rods engaged in said sleeves and a miter box having holes in the base portion thereof spaced apart a distance equal to the distance of the space between the sleeves of the gage device whereby said gage device and rods may be stored in the base portion of the miter box.
